WINDBOX FOR FURNACE

Leonard A. Fisher, Blandford, Mass., assignor to The H. B. Smith Company, Incorporated, Westfield, Mass., a corporation of Massachusetts

Filed July 9, 1964, Ser. No. 381,457
10 Claims. (Cl. 158—1.5)

This invention pertains to air admission directors or "registers" for fuel burners, in particular for forced draft burners—that embodiment of the invention herein disclosed being equally useful in oil, gas-oil, or gas burners. Briefly stated, the device of the present invention comprises a fan which supplies air tangentially to a cylindrical or conical wind-box which includes a perforated inner liner which defines the combustion zone—the liner being cooled by incoming air circulating between the liner and the outer wall of the shell or casing of the wind-box. To equalize the air pressure about the periphery of the liner, and resultant inflow of air through the perforations in the liner, an air distributing scroll or spiral diaphragm is arranged between the liner and the outer wall of the wind-box casing whereby the radial width of the passage thus defined, in which the air circulates, gradually diminishes from its entrance end to its discharge end, with provision for directing any air which does not pass inwardly through the perforations in the liner to move toward the axis of the flame.

The principal object of the present invention is to provide means wherein the perforated inner liner is so cooled by circulating air that it may be made of lower cost materials than is usually thought necessary in devices of this general type. This cooling of the liner makes it possible to design apparatus of this type with smaller dimensions than usual because the walls of the liner may be made thinner than when made of refractory materials, and as the liner is not exposed to so high a temperature as has been common heretofore, its useful life is increased since corrosion rates decrease rapidly as the temperature decreases. Such a relatively thin walled liner cools more rapidly than one made of heavy refractory materials thus reducing damage to the atomizers (and associated parts) during the off-cycles following firing periods and, on the other hand, because of the low thermal capacity of the liner as compared with liners made of heavy refractory materials, the burner comes to equilibrium temperature more quickly than usual when started into operation.

Furthermore, the atomizers or gas ports are not exposed to so high a radiant temperature as usual, with a corresponding increase in useful life, and since the cooler surface which surrounds the flame does not glow to the same degree as the usual refractory liner, a flame detector device, sensitive to the flame, is more positive in its action since it acts against a darker background.

Other objects and advantages of the invention will be pointed out in the following more detailed description and by reference to the accompanying drawings wherein:

FIG. 1 is an elevation, showing the device of the present invention mounted upon a truck to facilitate its assembly with and removal from the furnace—that side of the device being shown which faces the furnace;

FIG. 2 is a side elevation, omitting certain parts, of the device shown in FIG. 1;

FIG. 3 is a more-or-less diagrammatic rear elevation, to larger scale than FIG. 1, partly in vertical section, omitting the truck, but showing the shell of the wind-box and the fan casing, in accordance with one desirable embodiment of the invention;

2

FIG. 4 is a side elevation, partly in vertical section on the line 4—4 of FIG. 3;

FIG. 5 is a side elevation, to larger scale than FIG. 4, showing one desirable form of inner liner for the wind-box;

FIG. 6 is a vertical section substantially in the plane of the line 6—6 of FIG. 4, but to larger scale;

FIG. 7 is a side elevation of the wind-box shown in FIG. 6, omitting the liner, with the upper portion in vertical diametrical section;

FIG. 8 is a fragmentary vertical section, to larger scale, through the perforated inner liner showing the perforations therein and diagrammatically indicating the path of air circulating about the liner and moving inwardly through the perforations; and

FIG. 9 is a fragmentary vertical section illustrating the fan by means of which air is delivered to the wind-box.

Referring to FIGS. 1 and 2, the numeral 10 designates the outer, generally cylindrical shell or casing of the wind-box, this casing or shell being mounted upon a vertical plate 12 attached to or forming an integral part of a wheeled truck 11, thus facilitating the assembly of the wind-box with the furnace or its removal from the latter, the truck also supporting other parts, for example the burner motor and associated elements. The housing 13 (FIGS. 1 and 3) for the fan, which provides the forced draft to the wind-box, is also supported by the truck.

As shown in FIGS. 4 and 7, the outer casing or shell 10 is provided with a flange 13a designed to receive bolts or to be welded to the plate 12 for securing the shell to the plate. The shell (FIG. 3) has a tangential hollow arm 14 projecting from its peripheral wall and defining the terminal portion of an inlet passage 15, and has a terminal flange 16 (FIG. 3) to which there is connected, by bolts or otherwise, a flange 17 at the end of the discharge arm 18 of the fan housing 13—this housing having a central inlet opening 20 (FIG. 3) and encasing a rotary fan 21 (FIG. 9) mounted upon the shaft 22 of the fan motor 23—the latter having an attaching flange 24 which receives bolts for securing it to the fan casing at the opposite side of the latter from the opening 20. Desirably, an inwardly converging air-directing collar 25 (FIG. 9) is arranged within the opening 20 and is secured to the casing 19 of the fan by bolts 26. Within the passage 15 (FIG. 3) in the hollow arm 14 of the casing 13, there is arranged an air-controlling damper 27 (FIGS. 3 and 7) which is fixed to a shaft 28 by means of which it may be adjusted thereby to constrict the passage more-or-less and thus vary the velocity and quantity of air which enters the casing 10.

Within the casing 10 and concentric therewith is an inner liner 30 (FIGS. 4 and 5) which is here shown as cylindrical, and having the spaced, peripheral reinforcing ribs 31. While as here shown the liner is cylindrical, it is contemplated as within the scope of the invention to make it tapering or frusto-conical. As shown in FIGS. 4 and 5, this liner is provided with circumferentially extending rows of perforations 32. These perforations may, for example, be $\frac{1}{4}$ inch in diameter and the cylinder or liner may, for example, be of 14 gauge, stainless steel, that is to say, approximately 0.074 inch in thickness. At its left-hand end, as viewed in FIG. 5, the liner 30 has a flange or angle brackets 33 by means of which it is secured to the vertical supporting plate 12 as shown in FIG. 4.

The supporting plate 12 (FIG. 4) is provided with an opening 34 (FIG. 4) which is coaxial with the liner 30. A slightly convergent circular frusto-conical part 35 is

welded or otherwise secured at its larger end to the plate 12 in coaxial relation to the opening 34. The annular space between the liner 30 and the part 35 is filled with refractory material 36 in which is embedded the gas supply manifold 37 from which project the gas jet nipples 38—this gas manifold being supplied by a pipe 39, here shown as entering the shell 10 at its lower part.

Within the part 35 and concentric therewith there is arranged a frusto-conical tube 39 of lesser diameter than the part 35, thus defining the annular space 40 for the entry of primary air, if the latter be used. The annular space within the tube 39 is for the reception of a fuel atomizer F (FIG. 4) if oil is the fuel to be burned. The broken line C (FIG. 4) indicates the axis of the flame.

Within the discharge end portion of the casing 10, there is arranged a truncated, conical air-directing member 41 coaxial with the casing 10 and whose larger end is fixed, as by welding, to the casing 10. This member 41 is operative to discharge air, which does not pass inwardly through the perforations 32 of the liner 30, in a convergent stream toward the axis C of the burner flame. To prevent the air, thus discharged, from taking a spiral course, a series of radial vanes 42 (FIG. 3) is arranged within the cone 41.

In the annular space between the outer shell or casing 10 and the liner 30, there is arranged a scroll or spiral diaphragm 43 (FIGS. 3, 6 and 7), one end 43a of which (FIG. 6) is closely adjacent to the inner surface of the shell 10 at approximately the point of tangency of the wall 14a of the tubular branch 14 which connects the shell 10 and the fan casing—this scroll 43 progressively decreasing in diameter until it joins the opposite wall 14b of the part 14 at 43b, where its end is closer to the liner 30 than to the shell. The scroll, as here shown, encompasses the liner 30 through an arc of approximately 250°. Thus, the space S (FIGS. 3 and 6) between the scroll and the liner member 30 gradually decreases from the point at which the air from the fan first enters the space S, so that, although some of the air which enters the space S passes inwardly through the perforations 32, a substantially constant air pressure is maintained in space S. Thus approximately the same quantity of air enters the liner 30 from all sides. As shown in FIG. 8, air, indicated by the arrows A¹, flowing, under pressure, circumferentially about the perforated liner 30, enters the liner through the perforations 32 as shown by the arrows A² and flows along the inner surface of the liner thus acting to keep the liner cool. By automatically modulating the damper blade 27 so as to reduce the size of the discharge passage from the fan, the velocity may be increased to keep the liner 30 cool, while the volume decreases in proportion to the fuel rate. By so circulating cool air about and through the liner it is possible to employ stainless steel, for example, as the liner, rather than the heavier and more expensive refractory materials commonly employed, thus making it possible to reduce the dimensions of the device as compared with those commonly in use.

While one desirable embodiment of the invention has herein been illustrated and described by way of example, it is to be understood that the invention is broadly inclusive of any and all modifications which fall within the terms of the appended claims.

I claim:

1. A burner device which comprises a wind-box having an outer cylindrical casing and a liner of circular transverse section coaxial with and within the casing, the liner being of such diameter as to provide an annular space between it and the casing, the liner defining the space within which combustion takes place; characterized in that the liner is of sheet metal and of a thickness less than would be necessary were it to be made of a non-metallic, refractory material, the liner having a multitude of perforations therein spaced substantially uniformly about its entire periphery, means operative to deliver

air into said annular space in a tangential direction, and means so guiding said air that it moves peripherally about the liner in contact with the outer surface of the latter throughout its entire circumference and at a pressure such that some of the air passes through the perforations and moves circumferentially of the liner in contact with the inner periphery of the latter, thereby keeping the liner at a temperature below that which would cause deterioration of the sheet metal.

5 2. A burner device according to claim 1, having, in combination with the liner, a nozzle element for delivering fuel in an axial direction into one end of the liner, further characterized in that the liner is of a material having a thermal capacity which is lower than though it were made of usual non-metallic, refractory materials so that the burner comes into equilibrium temperature more quickly than usual when started into operation and cools more rapidly than were it made of refractory material, thereby reducing damage to the fuel delivery element 10 during an off-cycle following a firing period.

15 3. The combination according to claim 2, further characterized in having means operative to direct air which escapes from said annular space, without passing through the perforations in the liner, toward the axis of the burner flame, and means to prevent the air, so directed toward the axis of the burner flame, from rotating about said axis.

20 4. The combination according to claim 2, wherein scroll-shaped diaphragm is arranged within said annular space, encompassing the liner through an arc of approximately 250°, one end of the diaphragm being adjacent to the wall of the casing and the other end being adjacent to the outer surface of the liner thereby gradually decreasing the effective radial width of said annular space, 25 and so creating a substantially uniform air pressure circumferentially of the liner that air, passing through the perforations, enters the liner throughout substantially its entire circumference.

25 5. The combination according to claim 2, wherein the liner is of sheet metal of a thickness of the order of 0.074 inch, and wherein the perforations in the liner are of the order of 1/4 inch in diameter.

30 6. The combination according to claim 2, wherein, at the delivery end of the casing, a truncated conical ring is arranged within the annular space between the casing and the liner with its larger end adjacent to the wall of the casing and with its smaller end spaced from the liner thereby providing an annular discharge opening through which air from the annular space may move in a generally 35 conical annular stream toward the axis of the burner flame.

35 7. The combination according to claim 6, wherein the conical ring is provided with a series of peripherally spaced, internal, radial vanes operative to oppose circulatory motion of the air as it escapes from the smaller 40 end of the ring.

45 8. The combination according to claim 2, wherein both the outer casing and the inner liner are cylindrical, and each is provided at one end with a radial attaching flange, 40 said flanges lying in the same plane, and, in combination therewith, a wheeled truck comprising a rigid vertical plate, means securing said flanges to said plate, a motor-driven fan supported by the truck which is operative to deliver air into the annular space between the casing and liner, said vertical plate having therein an opening coaxial with the liner wherein there are arranged coaxial tubular members defining between them a passage for the entrance of primary air, and a nozzle within the inner 50 of the two concentric tubular members for delivering atomized fuel into the combustion chamber.

55 9. In combination, in a burner of the class described, a hollow cylinder which defines the combustion chamber, said cylinder having a peripheral wall of sheet metal 60 of a thickness less than would be necessary were the cyl-

inder to be made of non-metallic, refractory material, the wall having external axially spaced, peripheral stiffening ribs and having substantially uniformly spaced perforations in the intervals between the ribs, means for delivering atomized fuel in an axial direction into one end of the cylinder, and means operative so to direct a gaseous cooling medium as to cause it to flow peripherally of the cylinder in contact with its inner and outer surfaces, respectively, thereby to prevent destructive overheating of the cylinder.

10. The combination according to claim 9, wherein the cylinder which defines the combustion chamber is of stainless steel of the order of 0.074 inch in thickness, said cylinder being lighter in weight and of lesser external diameter than were the wall of the combustion chamber to 15 be made of non-metallic, refractory material.
